[57] CLAIM

The ornamental design for a finger guard for grinder, as shown and described.

DESCRIPTION

FIG. 1 is a front perspective of a finger guard for grinder, showing my new design;

FIG. 2 is a front elevation thereof;

FIG. 3 is a rear elevation thereof;

FIG. 4 is an elevation of one side thereof, the other side elevation being a mirror image;

FIG. 5 is a top plan thereof; and,

FIG. 6 is a bottom plan thereof.

The broken lines in FIG. 5 represent a hose clamp for securing the finger guard to the grinder motor housing and are included merely to show the environment inasmuch as they form no part of the design.
